(57) **CLAIM**

The ornamental design for a radio frequency identification reader, as shown and described.

DESCRIPTION

FIG. 1 is a perspective view of a radio frequency identification reader showing my new design;

FIG. 2 is a top plan view thereof;

FIG. 3 is a bottom plan view thereof;

FIG. 4 is a left side view thereof;

FIG. 5 is a right side view thereof;

FIG. 6 is a front elevation view thereof; and,

FIG. 7 is a rear elevation view thereof.
